Inventor.

UNITED STATES PATENT OFFICE.

GEORGE HAVELL, OF NEWARK, NEW JERSEY.

DESIGN FOR A MEMBER FOR HAIR-CURLING IRONS.

SPECIFICATION forming part of Design No. 30,093, dated January 31, 1899.

Application filed October 14, 1898. Serial No. 693,559. Term of patent 7 years.

To all whom it may concern:

Be it known that I, GEORGE HAVELL, a citizen of the United States, residing at Newark, county of Essex, State of New Jersey, have invented a certain new and original Design for a Member for Hair-Curling Irons, fully described and represented in the following specification and the accompanying drawings, forming a part of the same.

o The present design relates to a member or half part of a hair-curling iron, such member constituting half of the entire curling-iron; and the novel features of the design are shown in the annexed drawings, in which—

5 Figure 1 is a side elevation, and Fig. 2 a cross-section, upon line 2 2 in Fig. 1, with the view directed from the lower part toward the upper part of Fig. 1.

The member of the curling-iron is formed o with a body *a* and a handle-shank *b*, connected with the body by the half-round portion *c* and round portion *d*. The round portion *d* is inclined to the body, and the half-round portion *c* at similar angles, so that the 5 shank lies parallel with the body near one end of the same. The junction of each shank with

the portion *c* is ornamented with a ball *g*. The half part is provided with a thin flat triangular web *e* upon the inner side of the round portion *d*. The section in Fig. 2 shows 30 by hatching the half-round shape of the portion *c* and by shading the round form of the portion *d*, as well as the thin flat form of the web *e*. The portions *c* and *d* are connected by curves *c'*, so that these portions form, with 35 the body and shank, one-half of a round Gothic arch, with the web *e* within the apex of such half-arch.

It is apparent that this design is applicable to a member for glove-stretchers. 40

Having described my design, what I claim as new, and desire to secure by Letters Patent, is—

The design for a member of a hair-curling iron, as herein shown and described. 45

In testimony whereof I have hereunto set my hand in the presence of two subscribing witnesses.

GEORGE HAVELL. 45

Witnesses:

HARRY C. HAVELL,
THOMAS S. CRANE.
